UNITED STATES PATENT OFFICE.

ALBERT G. NEWMAN, OF STANHOPE, IOWA.

GRINDING-MILL.

1,311,614.

Specification of Letters Patent. Patented July 29, 1919.

Application filed November 19, 1915. Serial No. 62,352.

To all whom it may concern:

Be it known that I, ALBERT G. NEWMAN, a citizen of the United States, residing at Stanhope, in the county of Hamilton and 5 State of Iowa, have invented certain new and useful Improvements in Grinding Mills; and I do hereby declare the following to be a full, clear, and exact description of the invention, such as will enable others skilled 10 in the art to which it appertains to make and use the same.

This invention relates to mills, such as are used for the purpose of grinding feed, and the primary object of the invention is 15 to provide improved means, of simple construction, whereby the inner or male bur of a feed grinder is detachably held in position within the female bur, which means is operable, upon the insertion of foreign articles 20 within the burs, for automatically releasing the male bur from connection with the power driving shaft, so as to arrest the rotation of the male bur and eliminate the mutilation of the grinding faces of the male and female 25 burs.

With the foregoing and other objects in view this invention consists in such novel features of construction, combination and arrangement of parts as will be hereinafter 30 more fully described, illustrated in the accompanying drawings and claimed.

In describing the invention in detail reference will be had to the accompanying drawings wherein like characters designate like 35 and corresponding parts throughout the several views, and in which:—

Figure 1 is a side elevation of a fragment of the feed grinder constructed in accordance with this invention.

Fig. 2 is a longitudinal section through Fig. 1,

Fig. 3 is an end view of the burs of the grinder, and

Fig. 4 is a section through the male bur 45 showing parts disconnected.

Referring more particularly to the drawings, 1 designates the driving shaft of the feed grinder, which has the male bur structure 2 mounted thereon for rotation with the 50 shaft. The male bur structure 2, includes, the disk 3 which has a plurality of grinding teeth 4 formed upon its inner surface and arranged in concentric spaced relation about the disk, and the hollow truncated cone 5 which extends inwardly into the female bur

6, from the face of the disk 3 upon which the grinding teeth 4 are formed. The outer surface of the substantially frusto-conically shaped bur 5 is provided with recesses indicated at 7 through which the ground feed 60 travels. The interior of the female bur 6 is also provided with recesses 8 corresponding to the recesses 7. The female bur 6 has a transversely extending annular flange 9 formed upon its base end upon which flange, 65 teeth 10 are formed. The teeth 10 coat with the teeth 4, as is clearly shown in Fig. 2 of the drawings.

The disk 2 has a flanged collar 11 attached thereto, which flanged collar is mounted 70 upon the shaft 1 and is secured thereto by means of a set screw 12. The truncated cone section 5 of the male bur 2 is detachable from the disk 3, and is provided with a diametrically extending opening 14 adjacent its apex. The opening 14 is adapted 75 for alinement with an opening 15 extending diametrically through the shaft 1. The break pin 16, which is constructed of wood or analogous brittle material, is inserted 80 through the openings 14 and 15 and keys the section 5 of the male bur to the shaft 1 for rotation therewith.

The disk 4 is provided with a central recess or depressed portion 20, the wall of 85 which is inclined as is clearly shown at 21. The recess 20 which is formed in the inner face of the disk 4 is provided for receiving the reduced portion 22 of the frusto-conical section 5 of the male bur, as is clearly shown 90 in Fig. 2 of the drawing. The circumference of the reduced portion 22 is inclined, as is shown at 23, for snugly fitting against the wall of the recess 20.

Any suitable type of mill frame may be 95 used in connection with the burs illustrated and described in this application, without departing from the spirit of the invention.

In case foreign articles, such as rocks or 100 the like, get within the grinding machine, the resistance offered by these foreign articles will be sufficient to break the pin 16, which will stop or arrest the rotation of the truncated cone section 5 of the male bur 2 105 and prevent the mutilation of the grinding feed and faces of both the male and female burs.

In reducing the invention to practice, certain minor features of construction, com- 110

bination and arrangement of parts may necessitate alterations to which the patentee is entitled provided such alterations are comprehended within the scope of what is claimed.

5 What is claimed is:—

1. A grinding mill comprising a female bur consisting of a hollow frusto-conical body and an annular flange, a drive shaft 10 extending axially through said body and rotatable with relation thereto, a male bur consisting of a frusto-conical body mounted on said shaft within the female body and a disk head mounted upon said shaft in engagement with said flange, a bolt securing said head to said shaft against axial and rotary movement with relation thereto, the head securing the male body against axial movement with relation to the female body 15 and shaft, and a breakable pin connecting said male body and shaft for simultaneous rotation, said male body member being sep- 20

arate from and movable independently of said head when said pin is broken.

2. A grinding mill including a driving shaft, a male bur consisting of a hollow frusto-conical body and a disk head, said head being provided in its rear face with a recess having an inclined side wall, a forwardly extending annular flange on the front end of the body engaging in said recess and having an inclined outer side engaging said inclined wall of the recess, a bushing located in the rear end of said body and surrounding the shaft, a break pin passing through the body and the bushing and the shaft, and a bolt securing the head to the shaft.

25 In testimony whereof I affix my signature in presence of two witnesses.

ALBERT G. NEWMAN.
